HERBERTS ENGINEERING COMPANY, INC., OF NEW YORK, N. Y., A CORPORATION
OF DELAWARE.

DISPLAY OR ADVERTISING MECHANISM.

1,236,433.

Specification of Letters Patent. Patented Aug. 14, 1917.

Application filed June 3, 1910. Serial No. 564,847.

To all whom it may concern:

Be it known that I, HERMANN JOSEPH HERBERTS, a citizen of the United States of America, residing at 19 Mentmore Terrace, 5 London Fields, in the county of London, England, have invented new and useful Display or Advertising Mechanism, of which the following is a specification.

This invention relates to apparatus for advertising and displaying and its purpose is to exhibit articles and advertising matter in such manner as to attract attention.

To this end, the invention comprises means for causing said articles to move with no visible means of propulsion and preferably also to be sustained with no visible means of support.

More particularly defined, the invention comprises a surface preferably opaque and 20 means upon one side of said surface for causing articles upon the other side of said surface to be drawn against the surface and to be moved thereon.

In a preferred construction, the invention 25 includes means for producing a rotating magnetic field and a surface arranged to be cut by said magnetic field so that objects containing or composed of magnetic material will be supported by the magnetic field 30 against the surface and moved thereon.

Various constructions embodying the invention are illustrated in the accompanying drawings in which—

Figure 1 is a cross sectional elevation of 35 an apparatus worked magnetically;

Fig. 2 is a similar view of an alternate form of such apparatus;

Fig. 3 is a detail thereof;

Fig. 4 is a similar view in cross sectional 40 elevation of a third form;

Fig. 5 illustrates a sectional view disclosing a winding 2 as divided and having oppositely wound and connected parts;

Fig. 6 illustrates a similar modification, 45 the lower pole pieces extending upward;

Fig. 7 illustrates a method of supporting small non-magnetic articles;

Fig. 8 illustrates a coaxial section of a device provided with a flat wall for use in a 50 vertical position;

Fig. 9 represents an apparatus with a cone-shaped advertising base or wall;

Fig. 10 is an arrangement for exhibiting 55 hollow bodies;

Fig. 11 is a diagrammatic representation, 55 in plan view, of means for exhibiting ribbons or ring-shaped bodies parallel with the axis of the device; and

Fig. 12 is a detailed elevational view of a 60 similar device.

In the constructions illustrated in Figs. 1 to 4, the apparatus consists essentially of a surface upon which the articles to be exhibited are adapted to move, and of means for producing a magnetic field extending 65 through said surface and moving relatively thereto, to move and sustain the articles exhibited. Such a magnetic field may be produced by a permanent magnet or by an electromagnet. The movement of the field may 70 be attained by imparting movement to the magnet or electromagnet, or to pole pieces thereof, by suitable distribution of conductors carrying alternating currents of different phase, or by successively supplying 75 current to stationary electromagnets.

In Fig. 1, an electromagnet is employed, the core of which is 1 and the winding 2. It is provided with pole pieces 3 and 4, each comprising a central disk pressed by a nut 80 against a shoulder on the core 1 and laterally extending teeth 5. This electromagnet as a whole is adapted to rotate, being mounted in bearings 6, 7 which may be ball or roller bearings, but are best made oilless, for example by the use of graphite. The magnet is inclosed by the surface 8, upon which the articles to be exhibited move, and since the magnets simply rotate, its surface is cylindrical. Preferably, the surface consists of thin brass or other non-magnetic metal sheet secured to two disks 9 and 10, in or upon which the bearings for the core 1 are formed. The device may have a suitable stand 11 and a suitable ornamented top which however play no part in the action of the apparatus. The electromagnet is preferably rotated by means of the small electromotor 12 bearing on its spindle a worm 13 gearing with the worm wheel 14 upon the shaft 15 extending 100 from the core 1. As the winding 2 also rotates, it is necessary to provide sliding connections whereby current may be conveyed to the winding, and for this purpose slip rings 16 are mounted on, but insulated from, the shaft 15, and brushes 17 connected with the source of supply bearing thereon.

Preferably, the poles 5 are bent toward

each other so that the magnetic circuit between them can be completed by a comparatively short article placed on the outside of the surface 8. If desired, this metal surface 5 may be supplemented or substituted by a surface of paper, cloth, paint or enamel, or the like which will have a different coefficient of friction with most of the articles to be exhibited.

10 It will readily be understood that when any article partly or wholly made of magnetic material is placed on the outside of the surface 8, a part of the magnetic flux extending between the poles 5 will pass 15 through the article and tend to press it against the surface 8. If this pressure is sufficient, the friction produced thereby will prevent the article falling down under gravity, while when the article is slightly below the position for maximum flux there is 20 also a magnetic upward pull. When the electromagnet is rotated, the salient poles 5 adjacent to the article at start, will tend to draw the article with them and it will 25 therefore move around on the surface 8. If the article has itself a smooth surface—if for example, it is a round so called tin box—it will itself roll upon the surface 8 which enhances the attractive effect. It is 30 not of course necessary that the article should extend completely from one pole to the other, but so far as it comes sufficiently into the path of the flux to produce the necessary attraction, the desired end will 35 be attained. If, however, the tractive effect is greater at one end of the article than the other, there is a liability for the article to twist and run out of the field.

Even if the article extends from one pole 40 to the other, it may roll somewhat out of the position of the maximum attraction if its axis becomes tilted through any cause. This is compensated for by slipping on the surface if the friction is not too great 45 and striking effects may be attained by taking advantage of such slipping. Obviously, an inclination downward is particularly likely to cause the article to run out of the field and fall and it is therefore well to have 50 the lower pole pieces slightly leading on the upper ones.

In the modification shown in Fig. 2, the pole pieces 18 are made flat from iron stampings of approximately the form indicated in 55 Fig. 3. It is advantageous to expand the lower poles in the vertical direction at their outer ends so as to provide the maximum area for the passage of the flux across the non-magnetic gap necessarily interposed between the pole piece and the article to be 60 supported. In this example, the magnet is no longer positively rotated by the electro-motor 12, but the worm wheel 14 is put upon the shaft of the friction wheel 19 which 65 engages with the upper surface of one of the

pole pieces 18, or with a friction disk thereon. The core 1 of the electromagnet is made hollow and within it, is placed a hollow brass spindle 20 through which the conductors may be led; this spindle fits the hole 70 through the core only at the ends so as to diminish friction. In order that this construction may be suited to take short tins, it may be desirable to provide an extra pole piece 21 in the center, as indicated by Fig. 75 5. The winding 2 is then divided into two parts oppositely wound and connected, as illustrated in Fig. 5. Instead of such intermediate pole pieces, one or more of the lower pole pieces may be extended upward 80 as indicated in Fig. 6.

In the modification shown in Fig. 4, the electro-magnetic windings 2 are stationary and so also is the cylindrical core 3. This core has end pole pieces 22 which also complete the casing for the device. These pole pieces, as the drawing illustrates, are arched so as partly to complete the return magnetic circuit, thus making it possible to use a long coil 2 with a comparatively short surface of 90 the drum 8. The pole pieces are secured to the core and therefore are also stationary. Rotating pole pieces 23 are arranged in the middle of the core and comprise a hub carrying spokes and extended at their outer 95 ends at right angles to their length, as illustrated. This disk rotates upon a ball or other bearing 24 supported upon a collar 25 secured to the core. Preferably, a thin brass liner or bush is interposed between the pole 100 piece 23 and the core so that there may be no undue friction, due to contact of magnetized surfaces. The central pole piece is driven by an electric or other motor 12 through the friction disk 19 and the driving 105 surface 34 formed upon or attached to the piece. It is now no longer necessary to provide sliding connections for the supply of the windings 2, but as the wires require to enter at the bottom out of sight, it is necessary to make provision for carrying the connections past the rotating pole. This is conveniently done by embedding the wires in 110 a slot 1, in the core 3 or in a perforation extending therethrough. Notches 36 in the 115 pole pieces so modify the distribution of the flux as to assist in sustaining small articles against the lower part of the surface without permitting them to drop to the lower edge of the pole piece.

120 Permanent magnets may be employed alone as already stated; it is advantageous to curve the magnet so as to give it as great a length as possible for a given distance apart of the poles.

125 It will be clear that the surface upon which the articles exhibited move need not be cylindrical; it could be a flat wall as shown in Fig. 8 which may be disposed vertically or at any other suitable angle for effecting 130

a differential action upon the display object as arising from the force of gravity and the magnetic attraction, by avoiding that these forces are coincident and unidirectional.

5 The magnetic field could be produced by permanent or by electromagnets, arranged to be moved in any closed figure, the articles being either above or beneath the advertising base or wall. The latter arrangement 10 is illustrated in Fig. 9. Again the surface may, like a cylinder, present a closed cross section but not a circular one, *i. e.*, a cone-shaped surface as shown in the modification Fig. 9.

15 Reverting to the cylindrical structure already illustrated, it may be mentioned that various attractive effects can be obtained with different articles.

As stated a simple cylindrical article rolls 20 around the drum so as to expose in turn every side; such an article need not be entirely of magnetic metal, for example, a cardboard box with magnetic rims rotates perfectly well. A "tin" box of elliptical or 25 like cross section also rolls, rolling slowly so long as the flat part of its surface is presented to the drum and quickly when its sharply curved ends come against the drum. Thus the flat sides are exposed to view for 30 some while and then the tin practically turns over and exhibits the other side.

In general, non-magnetic articles may be exhibited by attaching to them a piece of magnetic material. In the case of hollow 35 articles this is conveniently done by putting a core inside the article. In this way, non-magnetic pencil cases, fountain pens and the like may be exhibited. The core need not by any means be large enough to fill the interior of the article. In the modification 40 illustrated in Fig. 10 the core 27 may be attached by radial pivoted arms 58 to the article 26 so as to support it positively instead of by friction only. Each of the cores 45 will roll around the drum and therefore the endless band will be carried around the drum and will, in turn, expose each part of its outer surface, as illustrated in Fig. 11, where 59 is the endless band and 37 the hollow core.

A detailed elevational view of such a core 55 is shown in Fig. 12, a flange being provided at both ends and the upper part of the core being fitted with any desirable ornamentation.

Non-magnetic articles may instead be supported and exhibited by means of a magnetic stand itself adapted to coact with the apparatus. Such a stand is illustrated in 60 Fig. 7 and comprises two disks 28 and 29 of magnetic material joined by a stem 30 which may also be magnetic. The disks form trays upon which the non-magnetic articles can be supported and the stem itself may be 65 prolonged and bear another article.

As at first indicated, the electromagnetic field required for the purpose of the invention may be produced simply by means of electric currents. If alternating currents of two or more phases and of suitable low frequency are supplied with suitably distributed conductors, a moving magnetic field is obtained which will serve the purpose of the invention. The ordinary frequencies of supply are, however, somewhat high for the purpose and would cause a rather rapid rate of rotation. For this reason it is better to employ direct currents and a commutator by which they are supplied in turn to a series of magnets. These magnets or the wound armatures replacing them should be so formed as to have opposite poles at different parts of their length.

What I claim is:—

1. An apparatus for advertising comprising a solenoid including a magnetic core, irregularly shaped pole pieces supported adjacent the core, a screen housing the core and pole pieces, and means for rotating at least one of the pole pieces for producing a moving magnetic field through the screen.

2. An apparatus for advertising comprising a solenoid including a magnetic core, pole pieces having teeth supported adjacent the core, a screen housing the core and pole pieces, and mechanical means for rotating at least one of the pole pieces for producing a moving magnetic field extending through said screen.

3. An apparatus for advertising comprising a solenoid including a magnetic core, pole pieces having teeth supported adjacent the core, a screen housing the core and pole pieces, said teeth operating adjacent the screen, means for rotating at least one of the pole pieces for producing a magnetic field through said screen surface and moving relatively thereto, substantially as described.

4. An apparatus for advertising comprising a solenoid including a magnetic core, end plates secured thereto and forming poles thereof, an intermediate plate magnetically associated with said core and movable relatively thereto, a surface surrounding said plates, means for producing a magnetic field through said core, plates and surface, and means for rotating said intermediate plate.

5. Apparatus for advertising or displaying comprising a magnet, elongated pole pieces associated therewith and each having a plurality of projections, a surface surrounding at least one of said pole pieces, and means for causing relative motion between said pole pieces and said surface.

6. Apparatus for advertising comprising a cylindrical housing, solenoids supported within the housing, pole pieces formed adjacent the ends of the solenoids, and means for rotating at least one of the pole pieces.

7. An apparatus for advertising or displaying comprising a solenoid, pole pieces having radial projections associated therewith, a surface surrounding said radial projections in proximity thereto, and means for causing relative motion between said radial projections and said surface.
8. An apparatus for advertising comprising a solenoid including a magnetic core, recurved pole pieces associated therewith, a surface inclosing the edges of said pole pieces, and means for producing a moving magnetic field extending through said pole pieces and surface.
9. An apparatus for advertising comprising a solenoid including a magnetic core, recurved end pieces magnetically associated therewith, a housing surface inclosing same, a central subdivided pole on said core, a driving rim attached to the said central pole or forming part thereof, and a motor frictionally engaging therewith for rotating
10. An apparatus for advertising comprising a solenoid including a magnetic core, pole pieces magnetically associated therewith, a surface surrounding said pole pieces, articles adapted to be supported on the surface, each of said articles comprising a cylindrical object and a cylindrical magnetic core operating therein, means for producing a moving magnetic field through said pole pieces and surface for attracting said last named magnetic core for moving the articles over the surface.
- 15
- 20
- 25
- 30
- 35
- said central pole within said housing surface.
- In testimony whereof I have signed my name to this specification in the presence of two subscribing witnesses.
